UNITED STATES PATENT OFFICE.

GEORGE W. HILL, OF BLUE RIDGE, MISSOURI.

DESIGN FOR A HAMMER.

SPECIFICATION forming part of Design No. 29,021, dated July 12, 1898.

Application filed June 20, 1898. Serial No. 684,004. Term of patent 14 years.

To all whom it may concern:

Be it known that I, GEORGE W. HILL, a citizen of the United States, residing at Blue Ridge, in the county of Harrison and State of Missouri, have invented a new and original Design for Hammers, of which the following is a specification.

In the accompanying drawings, Figure 1 is a perspective view of a hammer, showing my design. Fig. 2 is a front elevation, and Fig. 3 a rear elevation, thereof.

The leading features of my design consist in a hammer-head the upper surface of which extends in a curved line in substantially the arc of a circle from the crown to the tips of the claws, the under surface of the claw portion extending in a curved line, which joins the stock of the head at a point substantially midway its top and bottom, from which point a vertical flat rear face extends to the bottom, said head having a straight flat vertical front face from the crown to the neck of the head, with a substantially cylindrical striking-face projecting from the vertical flat front face about midway the extremities of the latter, and a nail-holder projecting downwardly from the striking projection at the juncture of the latter with the face of the hammer-head, as shown.

In said drawings the reference-numeral 1 indicates the hammer-head, mounted on a suitable handle 2. The upper surface of the hammer-head is extended, as shown in a curved line 3 4, in substantially the arc of a circle from the crown to the tips of the claws 35 and the under surface of the claw portion extends in a curved line 4 5 to a point about midway the top and bottom of the hammer-head. From this point there is a vertical flat rear face 6, extending to the bottom of the hammer-head. The front face 7 of the hammer-head, as shown, is vertical and flat, and about midway the extremities of the same there is a projecting substantially cylindrical striking-face 8, from the lower portion of which a 45 nail-holder 9 projects downwardly, as shown.

Having described my invention, what I claim as new, and desire to secure by Letters Patent, is—

The design for a hammer, substantially as herein shown and described.

In testimony whereof I have hereunto set my hand in presence of two subscribing witnesses.

GEORGE W. HILL.
